US00D697319S

(12) **United States Design Patent**
Brookman et al.

(10) **Patent No.:** **US D697,319 S**
(45) **Date of Patent:** **** Jan. 14, 2014**

(54) **SUBSTRATE WITH CAMOUFLAGE PATTERN**

(75) Inventors: **Amber Marie Brookman**, Westport, CT (US); **Thomas Jeronimo**, Swansea, MA (US)

(73) Assignee: **Brookwood Companies**, New York, NY (US)

(**) Term: **14 Years**

(21) Appl. No.: **29/431,796**

(22) Filed: **Sep. 11, 2012**

(51) **LOC (10) Cl.** **05-05**

(52) **U.S. Cl.**

USPC **D5/62**

(58) **Field of Classification Search**

USPC ..... D5/4, 43, 47, 50, 53, 55–63, 99, 6, 32, D5/37, 38, 66; D19/1, 5; D32/43; D6/582, D6/602, 612; 2/900; 5/490, 495; 15/208; 112/401, 416, 439; 139/383 R, 383 B; 428/32, 66.5, 85, 151, 152, 187, 542.6; D25/149; 442/408

(57) **CLAIM**

The ornamental design for a substrate with camouflage pattern, as shown and described.

DESCRIPTION

The file of this patent contains at least one drawing executed in color. Copies of this patent with color drawings will be provided by the Office upon request and payment of the necessary fee.

The sole FIGURE is a plan view of a substrate with camouflage pattern showing my new design. The broken lines define the boundaries of the claimed design and form no part thereof.
